UNITED STATES PATENT OFFICE

96,695

DESIGN FOR A BRUSH

Clyde A. Porter, Aurora, Ill., assignor to National Brush Company, Aurora, Ill., a corporation of Illinois

Application May 13, 1935, Serial No. 56,801

Term of patent 7 years

To all whom it may concern:

Be it known that I, Clyde A. Porter, a citizen of the United States, residing at Aurora, Illinois, postoffice address 460 Grand Avenue, Aurora, Illinois, have invented a new, original, and ornamental Design for a Brush, of which the following is a specification, reference being had to the accompanying drawing, forming part thereof.

Fig. 1 shows a perspective view of my new design for a brush with a substantially rectangular handle, particularly at the narrow gripping portion and at the top of the handle.

Fig. 2 is a front elevation thereof.

Fig. 3 is a side elevation of my new design for a brush.

Figs. 2 and 3 are drawn to a slightly smaller scale than Fig. 1.

I claim:

The ornamental design for a brush as shown and described.

CLYDE A. PORTER.
